UNITED STATES PATENT OFFICE.

WILLIAM H. RUSSELL, OF ST. CLAIR, PENNSYLVANIA.

CHARGE-HEATING ATTACHMENT FOR EXPLOSIVE-ENGINES.

1,153,448.

Specification of Letters Patent. Patented Sept. 14, 1915.

Application filed December 3, 1913. Serial No 804,365.

To all whom it may concern:

Be it known that I, WILLIAM H. RUSSELL, a citizen of the United States, residing at St. Clair, in the county of Schuylkill and 5 State of Pennsylvania, have invented certain new and useful Improvements in Charge-Heating Attachments for Explosive-Engines, of which the following is a specification.

10 My invention relates to explosive engines, and it consists in improved means for utilizing the exhaust to heat the inflowing charge as fully described in connection with the accompanying drawing and specifically 15 pointed out in the claim.

Figure 1 is a side elevation showing my invention applied to an explosive engine of known type; the latter, as well as the ordinary carbureter employed, being just sufficiently indicated to make clear the application. Figs. 2 and 3 are sectional views on the line 2—2 and 3—3 respectively, of Fig. 1.

The engine 1, as indicated, is of the ordinary four-cylinder type, having exhaust outlets 2, 2, 2, 2 connected to a single exhaust pipe 3, and inlets 4, 4 each of which leads to two adjacent cylinders having their centers at 6, 6, 6, 6. The exhaust pipe 3, as 25 shown, is formed with a return bend 5 at one end, which is adapted for connection to my specially formed inlet-pipe attachment as hereinafter described.

This attachment comprises, as shown, a main inlet-pipe 10 connecting the engine inlets 4, 4, and an integrally formed branch 11 having an outer-end portion 12 adapted for attachment to an ordinary carbureter 9 from which it receives the charging mixture. 35 Intermediately this branch 11, 12, is enlarged to provide an intersecting transverse exhaust passage-way 13, which terminates 40

at one side of the branch 11 in a suitable connection 14 for the return-end of the exhaust pipe 3, and at the other side in a 45 suitable exhaust-discharge connection 15; and to form a divided passageway 16 extending around the intermediate portion of said exhaust passage-way 13 and joining below the latter in the outer-end portion 12 50 of the inlet pipe 11.

It will be readily seen that the very simple and inexpensive construction described provides for preheating the inflowing charge from the carbureter, by passing 55 it completely around and in intimate contact with the heated walls of the exhaust passage 13, while at the same time providing an absolutely free exhaust discharge.

What I claim is:—

In combination with a carbureter and an explosive engine having exhaust and inlet ports and an exhaust pipe connecting said exhaust ports formed with a return-bend, a charge-heating attachment in the return- 65 bend portion of said exhaust pipe, said attachment comprising a separate integrally formed charge-and-exhaust connection having a transverse unobstructed exhaust-passage portion, and an annular charge-passage 70 portion surrounding the same, exhaust pipe connections at opposite ends of said transverse portion, and cylinder inlet-port connections and a carbureter connection at the opposite ends respectively of said annular 75 charge-passage portion substantially as shown and described.

In testimony whereof I affix my signature in presence of two witnesses.

WILLIAM H. RUSSELL.
